**APPARATUS FOR SEVERING FED STRANDS
AND SUBSEQUENT HANDLING THEREOF**

Donald W. Edwards, Wilmington, Del., assignor to E. I. du Pont de Nemours and Company, Wilmington, Del., a corporation of Delaware

Filed July 17, 1959, Ser. No. 827,901
6 Claims. (Cl. 83—100)

This invention relates to the handling of strands and, more particularly, to the processing of a plurality of strands advancing away from a continuously operating source.

The term "strand," as used herein, is intended to include either a single filament, a gathered plurality of such filaments, or the threads, yarns, narrow webs, and the like produced from filaments or from staple fibers.

It is well known in the textile industry that a spinning process, wherein filament-forming material is extruded from a spinneret, is normally not stopped when a defective condition arises during the handling steps which follow extrusion. Such defects are usually encountered in the form of roll wraps, breaks, or similar defects which appear in the downstream handling of the strands. Rather than interrupt the spinning process, the practice is for the operator to cut down all the strands and then introduce them to a fluid actuated aspirator of the type shown by Miller in U.S. Patent 2,667,964. Since it is also customary in the art to have a single operator patrol a multiplicity of spinning positions, it is obvious that a defective condition may go unnoticed for a considerable period of time with resultant damage to the process equipment and a consequent interference with orderly operating procedures. An alternative practice has been to employ sensing devices which function to detect the various defects and to actuate cut-down or stop-motion equipment thereby interrupting the downstream delivery from a given source. The extruded material is then permitted to accumulate on the floor beneath the spinning position until the operator has had a chance to remedy the sensed defect and restore the position to a normal operating condition. In such equipment, it is customary to provide a separate cutting device for each of the advancing strands.

The most important object of the present invention is to provide an improved process and apparatus for cutting down and disposing of all the strands advancing from a spinning position upon occurrence of a defect in one or more of the strands.

Another important object of the invention is the provision of an apparatus in which but a single cut-down device and aspirator are required for the plurality of strands advancing from a spinning position.

A further object of this invention is to provide a process and apparatus in which the cut-down device and aspirator are actuated directly and automatically in response to an undesirable operating condition.

With these and other objects in view, the apparatus of the present invention comprises generally the provision of a support situated adjacent the path of travel of the strands, severing means positioned at one side of the advancing strands, a gathering hook positioned at the other side of the strands, an actuator for moving the hook across the strand path of travel toward the severing means, an aspirator positioned adjacent the severing means for withdrawing the severed strands by suction, and a condition responsive element for initiating movement of the actuator and withdrawal of the cut strands by the aspirator. The process of this invention involves the steps of gathering the strands into a bundle, moving the bundle laterally to a severing zone, severing the

2

bundle and removing the severed, continuously advancing strands from the zone by suction.

Further advantages of the process and apparatus of the invention will become apparent in the following description wherein reference is made to the accompanying drawings in which:

FIGURE 1 is a plan view of the apparatus of the present invention shown in conjunction with a plurality of advancing strands; and

FIG. 2 is an elevational view of the apparatus shown in FIG. 1, parts having been broken away and shown in section to reveal details of construction.

In the drawings, a cut-down apparatus has been illustrated which apparatus comprises generally a support 10, strand-severing means 12, a strand-gathering hook 14, an actuator 16 for moving the hook toward the severing means, an aspirator 18 for withdrawing severed strands and a condition responsive solenoid valve 20 by means of which actuator movement is initiated.

A pair of leads 22 couple solenoid valve 20 to a sensing device (not shown) in which an electrical circuit is closed upon the detection of an abnormal operating condition. Valve 20 admits air under pressure into one of the conduits 24, 26. Conduit 24 discharges into the actuator 16, which has been illustrated as a double-acting piston-cylinder assembly, through a flow control valve 28. Conduit 24 simultaneously feeds aspirator 18, which may be of the type disclosed by Miller, through branch conduit 30. Conduit 26 discharges into the other end of the assembly 16. Hook 14 is attached to the piston rod 32 by an irregularly shaped arm 34. Arm 34 is apertured to receive a pin 36 which extends through a coil intermediate the ends of hook 14 and through arm 34 into threaded engagement with a stud 38. Hook 14, which is of a suitable spring metal, has one end anchored in an opening 40 in arm 34. A plurality of strands, indicated by the numeral 42, is restrained by one or more fixed guides 44, so that strands 42 pass axially through the area swept by hook 14 in its translatory movement towards severing means 12.

The severing means 12 chosen for illustration is a plate type knife which includes a fixed plate 46 and a pivoted knife blade 48. Blade 48 is attached to plate 46 by a pin 50 and a nut 52 which acts on a spring washer 54. The pivoted blade 48 is biased to the open position by a coil spring 56 which has one end 58 anchored to blade 48 and its other end 60 in engagement with a pin 62 on plate 46. Blade 48 has an abutment 64 which is within the path of travel of stud 38 upon translatory movement of the arm 34 so that blade 48 is closed against the bias of spring 56 when a bundle of strands is delivered thereto by hook 14. For best results, the blades should be of tool steel and the cutting edges should be ground.

After the strands have been severed by blade 48, they are picked up by and aspirated through a tube 66 of aspirator 18 to a suitable waste collection point.

In operation, therefore, energization of solenoid valve 20 by the sensing device admits air under pressure to actuator 16 and the aspirator 18 through conduit 24. All 60 of the strands 42, including those in which no defect has occurred, are gathered by hook 14 and delivered as a bundle to the severing zone from which the cut strands are withdrawn by aspirator 18. When the source of the defective strand condition has been remedied, the operator 65 inactivates the sensing device by throwing a laming switch (not shown) which functions to hold valve 20 in the de-energized position. After string-up and the like, the spinning position is placed in automatic operation by moving the laming switch to a position in which the sensing device 70 is in a ready condition.

The apparatus disclosed herein has utility in conjunction with any processing apparatus wherein one or more

strands pass axially between two process points. It may be employed, for example, in the cold drawing process disclosed by Sharp in U.S. Patent No. 2,851,732, in which instance the cut-down apparatus is installed at a location where the bundle has been subdivided into smaller bundles.

It is apparent that many changes and modifications may be made in the disclosed cut-down apparatus without departing from the spirit of the present invention which is accordingly intended to be limited only by the scope of the appended claims.

I claim:

1. In an apparatus for processing at least one continuously advancing strand: a support situated adjacent the path of travel of the strand; strand-severing means including a plate fixed on the support at one side of said path of travel and a blade pivotally mounted on the plate for swinging movement to and from a closed, strand-severing position; a hook normally positioned on the opposite side of said path from said severing means, said hook being mounted on said support for movement across said path to the vicinity of said severing means and including a part engageable with said blade for swinging the latter to said closed position; an actuator connected to said hook to facilitate its movement; and strand removal means situated adjacent said blade for picking up and disposing of the severed, continuously advancing strand.

2. In an apparatus for processing a plurality of continuously advancing strands: a support situated adjacent the path of travel of the strands; strand-severing means on the support at one side of said path; a strand-gathering element normally positioned on the opposite side of said path, said element being mounted on said support for movement across said path toward said severing means and including a part engageable with said severing means for its actuation; a fluid actuator connected to said element for moving it across said path; a suction device having an inlet positioned adjacent said severing means for picking up and disposing of gathered and severed continuously advancing strands; and condition responsive valve means coupled with the actuator and said suction device for the delivery of fluid thereto.

3. The apparatus of claim 2 wherein said strand-severing means comprises first and second knife blades respectively fixed to and pivoted on said support, and spring means biasing said second blade to an open position for receiving said strands, there being an abutment on said second blade within the path of travel of said part for pivoting said second blade to a closed position.

4. In an apparatus for processing a plurality of continuously advancing strands: a support; strand-severing

means including a plate fixed on the support at one side of the path of travel of the strands and a blade pivotally mounted on the plate; spring means biasing the blade to a strand-receiving position; a fluid actuated piston-cylinder assembly on the support; a strand gathering hook; means attaching the hook to the piston of said assembly for movement of the hook across said path toward said blade, the latter having an abutment thereon, said attaching means including a stud aligned with the abutment for pivoting the blade against the bias of said spring means, thereby actuating said severing means; an aspirator positioned adjacent said knife blade for picking up and disposing of gathered and cut continuously advancing strands; and a condition responsive valve coupled with the assembly and said aspirator for the simultaneous delivery of fluid thereto.

5. In an apparatus for processing at least one continuously advancing strand: a support situated adjacent the path of travel of the strand; strand-severing means mounted on the support at one side of said path of travel, said severing means including a fixed plate and a pivotally mounted knife blade; spring means normally biasing the blade to an open, strand-receiving position; a hook normally positioned on the opposite side of said path from said severing means, said hook being mounted on said support for movement across said path to the vicinity of said severing means and including a part engageable with said blade for pivoting the latter to a closed position against the bias of said spring means; an actuator connected to said hook for moving it across said path; and an aspirator having a tube terminating adjacent said severing means for picking up and disposing of the severed, continuously advancing strand.

6. The apparatus of claim 5 wherein said actuator is a double-acting piston-cylinder assembly and wherein a condition responsive valve is provided for simultaneously feeding fluid under pressure to said assembly and said aspirator.
